HONE CONDITIONING PROCESS

William O. Flatt, Fort Worth, Tex.

Application October 12, 1944, Serial No. 558,414

4 Claims. (Cl. 51—293)

This invention relates to abrasives and more particularly to the type known as hones which are specially adapted for use in sharpening and conditioning the brittle tempered steel of which razor blades are fabricated. Such hones are usually fashioned in the form of blocks. Whetstones of varying granular and cellular structure and carborundum or corundum blocks are exemplary of the type of hone to which my invention is eminently suited, although abrasives of various other types are suitable for honing and my invention is equally applicable to them.

Hitherto the primary object in processing abrasives, including hones, to enhance their wearing and sharpening characteristics has been to impregnate the pores of the material with some substance which possesses lubricating characteristics. The theory behind this objective seems to have been that by virtue of such impregnation the fatty substance with which the pores were filled would during the useful life of the hone migrate to the surface in quantities sufficient to form adequate lubrication for the grinding job. The suggestion that hones of the type here under consideration might be treated with grease, such as warm Vaseline, and then baked or burned until dry has been made heretofore. In some instances tallow base compounds have been used and in others synthetic resins of various types have been suggested as capable of performing the self-lubricating function over a substantial period of time.

The above described processing has proved satisfactory to a certain extent where a relatively large amount of heat is created during the grinding process and for that reason a substantial quantum of lubrication is necessary. This condition does not exist in the case of razor hones and I have found that oil or a greasy substance of any type used as a conditioner for hones soon forms along with the grit which invariably accumulates upon the working surface a pasty mass which clogs the pores of the stone and greatly impairs the sharpening characteristic of the working surface. This necessitates frequent processing to obtain a fresh working surface capable of satisfactorily honing the tempered steel of the blade.

My invention comprises an improved process whereby hones of the type referred to may be conditioned to improve their sharpening qualities over a substantially indefinite period of time. In contradistinction to the teachings heretofore available, I propose to so process the hone that the pores are thoroughly cleared and cleaned 55

throughout the whole mass of the material. As a result the abrasive working surfaces of the hone are accentuated. Hones of the type under consideration are quite porous and such porosity is emphasized as a result of my process to obtain a maximum hollow area within the body of the material, thus providing a maximum number of thin cutting edges on the working surface as repeated sharpenings wear away the face of such surface. These myriad minute cutting edges obtained by thoroughly cleansing the pores produce an excellent grinding action, and the difficulty referred to above resulting from the formation of a pasty mass on the working surface is entirely 15 eliminated.

Basically my process comprises the steps of immersing the hone in relatively light oil, preferably light machine oil, until it has absorbed a substantial quantity thereof. The hone is then 20 withdrawn and subjected to heat for a period of time sufficient to burn off the surface oil and to some extent the interior deposit. Because of the porous nature of the hone material, gas evolved during this initial oil burning step will 25 penetrate into the material, aiding the heat applied in opening the pores and preconditioning the material for the second step in the process.

When the flame from the surface oil is extinguished and the hone is still hot, it is again 30 immersed in the oil. The pores of the hone will fill very quickly this time and the oil penetrates from all sides deep into the body of the hone by virtue of the preconditioning step which has 35 opened the pores and cleared, to a large extent, the passages forming the interstices or pores between granular particles.

When substantially saturated and while still hot the hone is again subjected to heat sufficient to ignite the oil. There is an explosive ignition, 40 probably due to the gas evolution still taking place within the interior pores and the discharge from the surface pores, and the hone instantly becomes what may be described as a ball of fire. This second burning step is of sufficient duration 45 to burn substantially all of the oil out of the entire mass. The gas evolved during this second burning step passes through the pores and, as in the initial burning, functions to clear the same and condition the walls of the material surrounding the pores. By virtue of the deep penetration on the second immersion, gas is evolved throughout substantially the entire mass of the material and results in a hone uniformly processed throughout its entire mass.

For purposes of illustration and to assist in

visualizing the various steps of the process more clearly, reference is made to the drawing, wherein like numerals refer to like parts throughout the several figures, and wherein:

Figure 1 is a top plan view of one form of burner eminently suited to carry out the process described herein, and

Fig. 2 is a side elevation thereof.

The apparatus illustrated comprises a rectangular gas burner coil broadly indicated by the numeral 10 and fed from an intake 12. Within the rectangle is seated a frame, preferably formed of wire, comprising pairs of end supporting legs 14 and 16 extending diagonally upwardly and inwardly. Between the upper ends of each pair of legs the wire is formed into spaced pairs of transversely aligned pockets or seats 18 within each pair of which hones may be positioned in such manner that the ends thereof are located over a series of burner outlets 20.

After immersion of one or more hones in the manner here described, they are seated in pockets 18 in the manner illustrated in the drawing. The gas flame is turned sufficiently high to ignite the oil on the hone, then turned low but not completely off. The reason for not placing the body of the hone directly over the burner or heat source is because the dry heat therefrom, even when turned low, would have a tendency to bleach the lower edge of the hone, thereby adversely affecting its temper, upon which the sharpening qualities of the hone largely depend. When so positioned the hone will burn from both ends toward the center and will become enveloped with flame. The burner should continue in operation until the flame extinguishes itself, at which time and while the hone is still hot it is again immersed in the oil as aforesaid. By virtue of the hitherto described tendency to expand the pores and clear out the inner cellular structure of the hone, it will on this second immersion fill with oil very quickly and to the point of substantially complete saturation.

The hones are then placed over the burner in pockets 18 as hitherto described, except that each hone should be placed with that side seated in the pocket opposite to the side which was therein seated on the initial burning operation. The burning operation is repeated as hitherto described. Successive burnings from opposite edges insure uniform temper throughout.

After the hone has cooled it may be cleaned with some good cleaner readily obtainable in the market for that purpose. Soap should at no time be used because of the resultant closure of the pores of the hone, which would materially reduce the effectiveness of the cutting edges on the working surface and also tend in a short time to form the objectionable pasty mass to which reference has already been made.

It is believed that the remarkably durable and effective sharpening characteristics which distinguish a hone processed in accordance with my invention may be, in part at least, attributed to the substantial quantities of gas evolved from the relatively large amount of contained oil present during the second burning operation. This gas, evolved throughout the hone body by reason of

the relatively heavy saturation obtained on the second immersion, apparently creates a pressure sufficient to thoroughly clear the pores throughout the entire mass of the material rather than the surface only.

Having described my improved process in detail and illustrated one embodiment of an apparatus for satisfactorily performing the same, it will be understood that I do not wish to limit myself in any way to the means or mechanism illustrated for performing the various steps involved and for that reason I wish to limit myself only within the scope of the appended claims.

What I claim is:

- 15 1. That process of conditioning a razor hone which comprises the steps of immersing the same in oil, applying sufficient heat to a marginal portion thereof to ignite the surface oil, again immersing the hone while still hot for a sufficient time to obtain a condition of substantial saturation, applying sufficient heat to a different marginal portion thereof to ignite the surface oil, and permitting the resultant flame to burn until self-extinguishment occurs.
- 20 2. That process of conditioning a razor hone which comprises the steps of soaking the same in oil, applying sufficient heat to a marginal portion thereof to ignite the surface oil, reducing the quantum of heat applied to a minimum while permitting the resultant flame to burn until self-extinguishment occurs, immersing the hone while still hot for a sufficient time to obtain a condition of substantial saturation, applying sufficient heat in similar manner to a different marginal portion thereof to ignite the surface oil, and permitting the resultant flame to burn until self-extinguishment occurs.
- 25 3. That process of conditioning a razor hone which comprises the steps of impregnating the same with oil, applying sufficient heat to one marginal face thereof to ignite the surface oil, immediately reducing the quantum of heat applied to a minimum while permitting the resultant flame to burn until self-extinguishment occurs, again impregnating the hone while still hot with oil for a sufficient time to obtain a condition of substantial saturation, applying sufficient heat to the opposite marginal portion thereof to ignite the surface oil, and reducing the quantum of heat applied to a minimum while permitting the resultant flame to burn until self-extinguishment occurs.
- 30 4. That process of conditioning a razor hone which comprises the steps of impregnating the same with lubricant, applying sufficient heat to opposite ends of one edge of said hone to ignite the surface lubricant, reducing the quantum of heat applied to a minimum while permitting the resultant flame to burn until self-extinguishment occurs, again impregnating the hone while still hot with lubricant to obtain a condition of substantial saturation, applying sufficient heat to opposite ends of the other edge of said hone to ignite the surface lubricant, and permitting the resultant flame to burn until self-extinguishment occurs.
- 35 5. That process of conditioning a razor hone which comprises the steps of immersing the same in oil, applying sufficient heat to a marginal portion thereof to ignite the surface oil, again immersing the hone while still hot for a sufficient time to obtain a condition of substantial saturation, applying sufficient heat in similar manner to a different marginal portion thereof to ignite the surface oil, and permitting the resultant flame to burn until self-extinguishment occurs.
- 40 6. That process of conditioning a razor hone which comprises the steps of impregnating the same with oil, applying sufficient heat to one marginal face thereof to ignite the surface oil, immediately reducing the quantum of heat applied to a minimum while permitting the resultant flame to burn until self-extinguishment occurs, again impregnating the hone while still hot with oil for a sufficient time to obtain a condition of substantial saturation, applying sufficient heat to the opposite marginal portion thereof to ignite the surface oil, and reducing the quantum of heat applied to a minimum while permitting the resultant flame to burn until self-extinguishment occurs.
- 45 7. That process of conditioning a razor hone which comprises the steps of impregnating the same with lubricant, applying sufficient heat to opposite ends of one edge of said hone to ignite the surface lubricant, reducing the quantum of heat applied to a minimum while permitting the resultant flame to burn until self-extinguishment occurs, again impregnating the hone while still hot with lubricant to obtain a condition of substantial saturation, applying sufficient heat to opposite ends of the other edge of said hone to ignite the surface lubricant, and permitting the resultant flame to burn until self-extinguishment occurs.
- 50 8. That process of conditioning a razor hone which comprises the steps of immersing the same in oil, applying sufficient heat to a marginal portion thereof to ignite the surface oil, again immersing the hone while still hot for a sufficient time to obtain a condition of substantial saturation, applying sufficient heat in similar manner to a different marginal portion thereof to ignite the surface oil, and permitting the resultant flame to burn until self-extinguishment occurs.
- 55 9. That process of conditioning a razor hone which comprises the steps of impregnating the same with lubricant, applying sufficient heat to opposite ends of one edge of said hone to ignite the surface lubricant, reducing the quantum of heat applied to a minimum while permitting the resultant flame to burn until self-extinguishment occurs, again impregnating the hone while still hot with lubricant to obtain a condition of substantial saturation, applying sufficient heat to opposite ends of the other edge of said hone to ignite the surface lubricant, and permitting the resultant flame to burn until self-extinguishment occurs.
- 60 10. That process of conditioning a razor hone which comprises the steps of immersing the same in oil, applying sufficient heat to a marginal portion thereof to ignite the surface oil, again immersing the hone while still hot for a sufficient time to obtain a condition of substantial saturation, applying sufficient heat in similar manner to a different marginal portion thereof to ignite the surface oil, and permitting the resultant flame to burn until self-extinguishment occurs.
- 65 11. That process of conditioning a razor hone which comprises the steps of impregnating the same with lubricant, applying sufficient heat to opposite ends of one edge of said hone to ignite the surface lubricant, reducing the quantum of heat applied to a minimum while permitting the resultant flame to burn until self-extinguishment occurs, again impregnating the hone while still hot with lubricant to obtain a condition of substantial saturation, applying sufficient heat to opposite ends of the other edge of said hone to ignite the surface lubricant, and permitting the resultant flame to burn until self-extinguishment occurs.
